UNITED STATES PATENT OFFICE.

VIRGILIO AMBROGINI, OF HARRINGTON, WASHINGTON.

CAR REPLACER.

Application filed July 19, 1926. Serial No. 123,359.

The invention contemplates the use of a pair of complementary frog blocks adapted for use at the outer and inner sides of the rails of a track, and transferable in order that the derailed car or other rolling stock may be replaced by movement in either direction.

By the utilization of the car replacer of my invention the derailed car or trucks may, with facility be guided and shifted to position and deposited on the track rails without appreciable shock or jar to the rolling stock, and means are provided for securely anchoring the frog blocks against displacement in order that they may insure a stable support for the wheels as they are being replaced.

The invention consists in certain novel combinations and arrangements of parts as will hereinafter be more fully set forth and claimed.

In the accompanying drawings I have illustrated one complete example of the physical embodiment of my invention wherein the parts are combined and arranged in accord with the best mode I have thus far devised for the practical application of the principles of my invention.

Figure 1 is a perspective view showing the frog blocks of the car replacer in position with relation to the track rails for replacing a car.

Figure 2 is an enlarged detail vertical sectional view transversely of a track rail and the frog block at the left in Figure 1.

Figure 3 is a view in elevation view at the side of a rail showing the fastening or clamping means for a frog block to a rail.

Figure 4 is a vertical transverse sectional view of a rail and the frog block at the right in Figure 1.

In order that the general arrangement of and relation of parts may readily be understood I have indicated the cross ties as T and the track rails as R and R'.

The car replacer comprises a pair of complementary frog-blocks designated as a whole by the numerals 1 and 2 which are fashioned in suitable manner as from wrought metal, preferably hollow, and designed for use at the inner and outer sides of the complementary track rails. In Figure 1 the frog blocks are arranged in position to replace a car moving to the right, but it will be understood that the blocks may be turned end for end with the block 1 at the outer side of the rail R and the block 2 at the inner side of the rail

R' for the purpose of moving a car as to the left of Figure 1. The outer block 1 is used at the outside of the rail while the frog block 2 is used at the inner side of the opposite rail. 60

The outer frog block 1 is fashioned with an upwardly curved convex face 3 and an outer curved edge 4 which rises at its maximum height above the top of the tread of the rail R'. The curved face 3 of the frog block merges into a downwardly and inwardly declining face 5 in order that when the flanged wheel of the car rides up over the face 3 with the tread of the wheel over the arcuate edge 4, the wheel will be shifted 65 to the left in Figure 1 and the wheel flange will slide laterally over the inclined face 5, to the tread of the track rail. As the car truck is being guided by the other frog block, the flange of the wheel rolls over the 70 tread of the rail R' until the wheel is in position and replaced on the rail R'.

The inner or guide frog block 2 also has a curved, convex front face as 6 over which the wheel flange rides to position between 80 two guide flanges 7 and 8 of the frog block 2. Like the arcuate edge 4 of frog block 1 these flanges 7 and 8 extend diagonally with relation to the longitudinal axis of the blocks and of the track rails, and between the 85 flanges 7 and 8 a groove 9 is formed for the flange of the wheel to roll through.

As seen in Figure 1 the short guide flange 7 terminates flush with the top of the tread of the rail R and its inner wall or face 90 merges flush with the inner face of the rail head. Thus as the flanged wheel rolls up the groove 9 the flange is guided to shift the wheel laterally so that its tread will roll on the tread of the rail R and when this position is reached the flange of the wheel guides the wheel and truck to proper position on the two rails. 95

For strengthening and bracing the frog blocks they are fashioned with longitudinally extending flanges 10 and 11 that fit closely against and conform to the shape of the track rails, and thus afford the proper support for the load as the wheels pass over the frog blocks. 100

The two blocks are held in rigid relation to their respective rails by clamping means attached to or carried by each frog block. As these fastening devices or clamps are of duplicate construction and operation, a description of one will suffice for both. 110

A draw bar 12 which extends transversely

of the frog block is bolted or otherwise secured at the underside of the block, and this bar is of sufficient length to be slipped under the flanged base of the track rail with its free end at the edge of the base opposite to the side of the rail at which the block is located.

A removable bearing block 13 having a stud 14 is adapted to seat in a socket or hole 15 (dotted lines Figure 3) in the free end of the draw bar 12, and a bolt, as 16 having a head 17 is threaded through a horizontal opening in the block 13. By turning this bolt against the web of the track rail as indicated in Figures 2 and 4, it will be apparent that the braces 10 and 11 are brought into close proximity to the rails R and R' to hold the frog blocks in rigid position with rela-

tion to the pair of rails. After the car has been replaced, the bolts are loosened, and the bearing blocks 13 removed, thus releasing the draw bars, and then the frog blocks may be removed until further required for use.

Having thus fully described my invention, what I claim as new and desire to secure by Letters Patent is:

A car replacer comprising a pair of transferable, outer and inner frog blocks having longitudinally extending flanges conforming to the track rails, and means for clamping said frog blocks at the sides of said rails comprising a draw bar having a socket, a detachable bearing block having a stud in the socket, and a bolt in said bearing block.

In testimony whereof I affix my signature.

VIRGILIO AMBROGINI.
